Ornays.

UNITED STATES PATENT OFFICE.

SIMON MYERSON, OF CAMBRIDGE, MASSACHUSETTS.

MOUNT FOR ARTIFICIAL TEETH.

Application filed December 21, 1925. Serial No. 76,928.

This invention relates to a mount which includes a holder and a penetrable filler of material such as wax, supported by the holder, and having a face adapted to be penetrated by pins projecting from the posterior faces of teeth, the material of the filler adhering to pins inserted therein, so that the teeth are adequately secured to the mount and readily removable therefrom.

10 The chief object of the invention is to provide a mount, the holder element of which is of sheet material such as aluminum, and is adapted to firmly support the penetrable filler and teeth engaged therewith, said holder element being light and durable, neat and attractive in appearance, and adapted to be manufactured at a minimum expense.

Another object is to enable the holder and the penetrable body filler to enter a tooth recess formed in part by the posterior face from which the pins project.

Of the accompanying drawings forming a part of this specification—

Figure 1 is a perspective view of one form of the holder element.

Figure 2 is a section on line 2—2 of Figure 1.

Figure 3 is a view similar to Figure 2, showing the penetrable filler.

Figure 4 is a view similar to Figure 3, showing a recessed tooth engaged with the mount.

Figure 4^a is a view similar to Figure 4, showing a modification.

Figures 5, 6, 7 and 8 are views similar to Figures 1, 2, 3 and 4, respectively, showing a different form of mount and a differently formed tooth engaged therewith.

The same reference characters indicate the same parts in all of the figures.

The holder element includes a body portion 12 and flange portions at opposite edges of an opening 15 in the body portion, the holder being preferably made from a single sheet of aluminum. The flange portions may project outward from the body portion, as shown by Figures 1, 2, 3, 4 and 4^a, or inward, as shown by Figures 5, 6, 7 and 8.

16 designates a penetrable filler, preferably composed of wax. Said filler closes the opening 15 and bears on the flange por-

tions, and has a face which is exposed at the outer side of the holder and is penetrable by pins 17 projecting from the posterior face 18 of a tooth.

The exposed face of the filler and the flange portions shown by Figures 1 to 4^a, collectively form a seat for the posterior face 18.

Owing to the outward projection of the flange portions, the said seat is offset outward from the body portion 12, and is adapted, as shown by Figures 4 and 4^a, to enter a tooth recess, one side of which is formed by the posterior face 18. The seat may be inclined relative to the body portion, as shown by Figures 3 and 4, or parallel with the body portion, as shown by Figure 4^a. The outwardly projecting flange portions, shown by Figures 1, 2, 3 and 4, include a flange portion 14, perpendicular to the body, and a flange portion 13, inclined relative to the body. The flange portions 13^a and 14^a, shown by Figure 4^a, are each inclined relative to the body.

The holder shown by Figures 5 to 8, includes a body portion 12 and two oppositely inclined flange portions 20, projecting inward from the body portion at opposite edges of the opening 15 therein. The filler here designated by 16^a bears on the flange portions 20, and has a face which is exposed at the outer side of the holder and is substantially flush therewith. In this embodiment of the invention, the seat for the posterior face 18^a of the tooth is formed collectively by the body portion 12, and the exposed face of the filler 16^a as shown by Figure 8.

To compensate for the thinness of the sheet material, and provide a mount, the outer surface and tooth seat of which may be suitably elevated above a drawer bottom, or other support on which the mount rests, I provide supports 21 at opposite edges of the body portion, adapted to bear on a supporting surface and raise the body portion therefrom. Said supports are preferably provided by bending edge portions of the blank from which the holder element is formed, thus forming downwardly projecting ears. Said supports or ears maintain the body portion spaced above a supporting surface, and,

in the form shown by Figures 5 to 8, provide room under the body portion for the reception of the flange portions and the penetrable filler.

- 5 It will be seen that if the supports 21 were not provided, the flat body portions 12 of a collection of mounts deposited on a drawer bottom, would be liable to become entangled with each other, some body portions over-
10 lapping others.

I claim:

1. A mount for artificial teeth, comprising a holder of sheet material, including a body portion and outwardly projecting flange portions at opposite sides of an opening in the body portion, one of said flange portions being perpendicular and the other inclined relative to the body portion, and a penetrable filler closing the opening and bearing on the flange portions, and having an exposed face which is penetrable by a pin projecting from the posterior face of a tooth, the exposed face of the filler and the flange portions collectively forming a seat which is

inclined relative to the body portion and is 25 adapted to enter a tooth recess formed in part by said posterior face.

2. A mount for artificial teeth comprising a holder of sheet material including a body portion provided at opposite edges with supports, and having outwardly projecting flange portions at opposite sides of an opening formed in the body portion, one of said flange portions being perpendicular and the other inclined relative to the body portion, 30 and a penetrable filler closing the opening and bearing on the flange portions, and having an exposed face which is penetrable by a pin projecting from the posterior face of a tooth, the exposed face of the filler and 35 flange portions collectively forming a seat which is inclined relative to the body portion, and is adapted to enter a tooth recess formed in part by said posterior face.

40 In testimony whereof I have affixed my 45 signature.

SIMON MYERSON.
